UNITED STATES PATENT OFFICE.

JOHN HEBERLING, OF ROCHESTER, NEW YORK.

DUMPING-WAGON.

1,142,325.

Specification of Letters Patent.

Patented June 8, 1915.

Application filed December 11, 1911. Serial No. 664,995.

To all whom it may concern:

Be it known that I, JOHN HEBERLING, of Rochester, in the county of Monroe and State of New York, have invented a new and useful Improvement in Dumping-Wagons, which improvement is fully set forth in the following specification and shown in the accompanying drawings.

The present invention relates to dumping wagons of the type in which flexible connections are employed for controlling the doors or movable dumping sections of the wagon body, an object of this invention being to provide a construction having a slack take-up device for one of the connectors so constructed and arranged that the jar or strain, due to the sudden opening of the doors, is not imposed upon said take-up device, the latter being engaged by the flexible connections only as the doors approach closed position.

Another object of the invention is to construct this take-up device so that it will equalize the strain on the connections.

To these and other ends the invention consists in certain parts and combinations of parts all of which will be hereinafter described, the novel features being pointed out in the appended claims.

In the drawings, Figure 1 is a vertical longitudinal section through a dumping wagon constructed in accordance with this invention; Fig. 2 is a vertical transverse section showing the front of the winding means just prior to the closing of the movable doors or sections; Fig. 3 is a detail view of the winding means, showing the position of the equalizer when the doors are closed; Fig. 4 is an enlarged axial section of the winding shaft, showing the position of the equalizer when the doors are fully open; Figs. 5, 6 and 7 are three views of a modification of the invention, Fig. 7 being a section on the line b—b Fig. 5; Figs. 8 and 9 are detail views of a modification in which the take-up device is not in the form of an equalizer, Fig. 8 being a front view of the front end of the wagon body and the winding means, and Fig. 9 being a broken longitudinal vertical section of the wagon body; and Fig. 10 is a transverse section through a winding shaft of another embodiment of the invention.

In carrying out this invention, a wagon body of any suitable construction may be employed. In the present instance, the body consists of a front end board 1 and a back

end board 2 connected by side boards 3 which are extended in front of the front board and in rear of the rear board. The body may have two doors or sections 4 preferably hinged at 5 to the side boards 3 and one of said doors having a batten strip 6 at its free edge for overlapping the free edge of the other door.

For controlling the doors, two flexible connectors 7 and 8 may be provided, said connectors, in this instance, being separate from each other and each being attached at 9 to a hook on the rear board 2, thence extending forwardly along the free edges of one of the doors 4 over guides 10 to a guide 11 arranged on the front board of the body, the front ends of the connectors being attached at 12 to a winding drum or shaft 13 which is journaled on the side pieces 3 at the front of the vehicle. For winding the flexible connector on the winding means or the winding shaft, there may be provided a hand lever 14 turning on the shaft 13 and carrying the pawl 15 which co-operates with a ratchet wheel 16 rigid with the shaft 13.

Also co-operating with the ratchet wheel 16 is a locking pawl 17 pivoted at 18 to a swinging member 19 which, in turn, is pivoted at 20 to the forward extension of one of the side frames 3 and has a bifurcated portion 21.

Operating between the arms of the bifurcated portion is a pin 22 carried by a swinging foot-operated member 23. When the pin is located out of engagement with the arms of the bifurcated portion 21, the pawl 17 will ride over the ratchet 16 and hold the latter in any position to which said ratchet may be adjusted by the lever 14. When the pin is located in engagement with the upper arm of the bifurcation the pawl 17 is thrown out of engagement with the ratchet wheel 16 permitting the drum to unwind. When the pin 22 engages the lower arm of the bifurcation, the member 19 is held against movement so that, during the travel of the vehicle, the pawl 17 cannot be accidentally disengaged from the ratchet 16.

The foregoing parts are not claimed *per se* in this application, a feature of this invention being the provision of a slack take-up device for one of the flexible connectors and preferably the one which controls the door or section carrying the batten strip 6, so the other door may close first and then be overlapped by the batten strip, the

take-up device, when the doors are open, lying out of contact with the flexible connector so that the jar or strain, due to the opening of the doors, is not imposed upon the 5 take-up device.

According to the embodiments of the invention shown in Figs. 1 to 7, the slack take-up device is in the form of an equalizer which equalizes the strain on the two flexible 10 connections, so that the weight of the load will not be imposed on one connection, thus subjecting the latter to breaking.

In the embodiment shown in Figs. 1 to 4, the equalizer is in the form of a member 24 15 pivoted to the winding shaft 13 to turn about an axis 25 extending transversely of the axis of said shaft 13, the member being secured to the shaft between the connector attaching points 12 so, that both connectors 20 may engage with the equalizer. The equalizer has a tendency to swing outwardly to the position shown in Fig. 4 and this tendency is effected by making the outwardly swinging end 26 heavier, so that, when the 25 winding shaft rotates rapidly on the unwinding of the flexible connectors, the heavier end will swing outwardly under the action of centrifugal force.

To the end that the connectors will be directed toward the equalizer or take-up upon the winding of said connectors, the shaft may be formed with right-and left-hand spiral grooves 27, each leading from one of the attaching points 12 toward the equalizer.

30 As the shaft 13 is turned, the connectors 7 and 8 follow in the grooves 27, the connector 7 first engaging the equalizer by entering the groove 28 thereof, thus holding the adjacent end of the equalizer against 35 the shaft 13. The other connector 8 then engages within the groove 29 of the equalizer and, as the adjacent end is separated from the shaft 13, more of the connector 8 will be taken up and the door 4 controlled 40 thereby will move in advance of the door carrying the batten strip 6. After the door controlled by connector 8 reaches the closed position, a further turning of the shaft 13 will cause the equalizer to turn on its pivot 45 and assume the position shown in Fig. 3, thus taking up the slack in the connector 7 and causing the door with batten strip 6 to close with equal strain on both connectors 7 and 8.

50 In the embodiment of the invention shown in Figs. 5 to 7, the shaft 13 is provided with the grooves 27 leading from the connector attaching points 12 to an equalizer. The latter, in this instance, comprises a pivoted 55 or rocking member 30 secured to the shaft 13 by straps 31 to turn about an axis extending longitudinally of the shaft 13. The opposite ends of the rocking member 30 carry arms 32 preferably extending in opposite directions from the axis of the shaft,

so that one of said arms will be engaged by one of the flexible connectors before the other arm is engaged by the other flexible connector. In this way, the arm, that is engaged second, takes up more of its connector than the arm engaged first, thus moving one of the doors in advance of the other until such door is closed, when the strain on the connectors causes the member 30 to shift and equalize such strain on both connections, at the same time, effecting the closing of one door in advance of the other. 70 75

In the embodiment of the invention shown in Figs. 8 and 9, the shaft 13 is provided with grooves 27 in which the connectors 7^a and 8^a are wound. The connector 8^a is shorter than the connector 7^a, while the latter is provided with a turn buckle 33 or other device for varying the length of said connector 7^a. The slack take-up device is in the form of a projection or enlargement 34 on the winding shaft or drum 13 engaging the connector 7^a as the door controlled by the connector 8^a nears the end of the closing movement, the projection 34 causing the connector 7^a to be taken up faster, at this time, than the connector 8^a and thus closing the door carrying the batten strip 6 about the time that the other door closes. The turn buckle 33 permits the adjustment of the connector 7^a so that the tension on the connectors 7^a and 8^a will be equal. 90 95

In the embodiment shown in Fig. 10, the operation of the parts is similar to that of Fig. 9, an adjustable projection 34^a in the form of a curved strip of sheet material is secured at one end at 35 and has the other end engaged by an adjustable support 36 in the form of a screw extending through the shaft 13 and held against movement by a lock nut 37. With this construction it is unnecessary to provide adjustment in one of the flexible connections, as the adjustment of the projection will take-up for any slight difference in lengths between the two 100 105 connectors. 110

From the foregoing, it will be seen that there has been provided in all embodiments a slack take-up device which is not engaged by the flexible connectors until the doors 115 near closed position, and, in this way, the wear on the take-up is reduced to a minimum. At the same time, the take-up is mounted on the winding means and is in full view of the operator of the wagon so 120 that he may be assured that such take-up is operating properly.

Another important advantage for the arrangement of the take-up is that the latter is not affected by the position of the wagon 125 body and therefore the doors may be closed upon a hillside while the wagon is in an inclined position, the doors operating so that the one without the batten strip will be the first to close. 130

What I claim as my invention and desire to secure by Letters Patent is:

1. A dumping wagon of the type having doors, flexible connectors for controlling the doors and a winding shaft for the flexible connectors combined with a take-up device for the slack of the connectors, said take-up device being arranged on the winding shaft so as not to be engaged by the connectors during the first part of the winding movement but to engage at least one of the connectors during the latter part of the winding movement so as to take up slack therein.
2. In a dumping wagon, a body having at least two doors, a pair of flexible connectors, one for each door, a winding means engaging both of said connectors, and a device on the winding means lying out of engagement with said connectors when the doors are fully opened and engaged by one of said connectors as the doors approach closed position to take up slack in said connector.
3. In a dumping wagon, a body having at least two doors, a pair of flexible connectors, one for each door, a winding shaft for said connectors having a spirally formed groove, and a slack take-up independent of said groove arranged on the winding shaft at one end of the groove and having one of the connectors carried by said groove to said slack take-up after the door controlled by the other connector has closed.
4. In a dumping wagon, a body having at least two doors, a pair of flexible connectors for controlling said doors, and a pivoted equalizer for said connectors disengaged by the connectors on the opening of the doors and engaged on opposite sides of the pivot by said connectors as the doors approach closed position.
5. In a dumping wagon, a body having at least two doors, a pair of flexible connectors, one for each door, winding means engaging both of said connectors, and an equalizer arranged out of the path of the connectors when the doors are opened but engaged by both of said connectors as the doors near closed position.
6. In a dumping wagon, a body having at least two doors, a pair of flexible connectors, one for each door, a winding shaft for said connectors and equalizing means carried by the winding shaft, said equalizing means lying out of engagement with

said connectors when the doors are fully opened and being engaged by both of said connectors as the doors approach closed position.

7. In a dumping wagon, a body having at least two doors, a pair of flexible connectors, one for each door, a winding shaft to which said connectors are independently secured each at one of its ends, and a member pivoted to the shaft and engaged by both connectors between their ends to equalize the strain thereon.

8. In a dumping wagon, a body having at least two doors, a pair of flexible connectors, one for each door, a winding shaft for said connectors, and a pivoted equalizing member carried by the shaft and adapted to be engaged by the connectors on opposite sides of its pivot, said pivoted member having one end engaged by one connector in advance of the engagement of the other end by the other connector.

9. In a dumping wagon, a body having at least two doors, a pair of flexible connectors, one for each door, a winding shaft for said connectors, an equalizing member pivoted to the shaft to swing about an axis arranged transversely of said shaft, one end of the pivoted member being heavier than the other, in order that said end will be thrown outwardly on the rotation of the shaft in unwinding, thus taking up one connector in advance of the other on the winding of said connectors.

10. In a dumping wagon, a body having at least two doors, a pair of flexible connectors, one for each door, an equalizer for the connectors, and a winding shaft for said connectors having a right and a left-hand spirally-formed groove in which the connectors are wound, and said grooves being arranged to move said connectors onto and off of the equalizer.

11. In a dumping wagon, a body having at least two doors, a pair of flexible connectors, one for each door, a winding shaft having a right and a left spirally formed groove in which the connectors are wound, and a movable equalizing member mounted on the shaft between the grooves and engaged by both connectors.
